(57) **CLAIM**

The ornamental design for a media player display screen with graphical user interface, as shown and described.

DESCRIPTION

FIG. 1 is a front view of a media player display screen with graphical user interface according to the present disclosure showing a first image in an animated sequence;

FIG. 2 is a second image thereof;

FIG. 3 is a third image thereof; and,

FIG. 4 is a fourth image thereof.

The appearance of the transitional image sequentially transitions between the images shown in FIGS. 1-4. The process or period in which one image transitions to another forms no part of the claimed design.

The dot-dash lines illustrate the display screen and a boundary, and form no part of the claimed design.

1 Claim, 1 Drawing Sheet
